[57] CLAIM

The ornamental design for a jewelry clasp, as shown and described.

DESCRIPTION

FIG. 1 is a top plan view of a jewelry clasp showing my new design;

FIG. 2 is a side plan view thereof, the opposite side being a mirror image thereof;

FIG. 3 is a front plan view thereof;

FIG. 4 is a rear plan view thereof; and,

FIG. 5 is a top perspective view thereof.

The broken line showing of a crest in FIGS. 1, 3, 4, and 5 and apertures in FIGS. 1 and 2 are for illustrative purposes only and form no part of the claimed design.

FIG. 1

FIG. 5

FIG. 2

FIG. 3

FIG. 4
